UNITED STATES PATENT OFFICE.

JAMES HENRY EGBERT, OF ANACONDA, MONTANA, ASSIGNOR OF ONE-HALF
TO JOHN S. HICKEY, OF ANACONDA, MONTANA.

STUB-AXLE FOR CARS.

SPECIFICATION forming part of Letters Patent No. 687,212, dated November 26, 1901.

Application filed January 22, 1901. Serial No. 44,289. (No model.)

To all whom it may concern:

Be it known that I, JAMES HENRY EGBERT, a citizen of the United States, residing at Ana-
conda, in the county of Deerlodge and State
5 of Montana, have invented a new and useful
Stub-Axle for Cars, of which the following is a
specification.

The invention relates to improvements in
stub-axles for cars.

10 The object of the present invention is to im-
prove the construction of axles for mining-
cars and the like and to provide simple and
comparatively inexpensive axles adapted to
be readily applied to mining and other cars
15 and capable of providing a strong construc-
tion and of facilitating lubrication of the
parts.

20 A further object of the invention is to pro-
vide a stub-axle adapted to be readily removed
and capable of being lubricated independ-
ently of the other axles of a car; and another
25 object of the invention is to enable the bear-
ing-sleeves for the reception of the axles to
be firmly interlocked with the body of a car
and to prevent the latter from being strained
by the independent attachment of the axles.

The invention consists in the construction
and novel combination and arrangement of
parts hereinafter fully described, illustrated
30 in the accompanying drawings, and pointed
out in the claims hereto appended.

35 In the drawings, Figure 1 is a reverse plan
view of a portion of a mining-car constructed
in accordance with this invention. Fig. 2 is
an enlarged sectional view taken longitudi-
nally of one of the axles. Fig. 3 is a sec-
tional view taken transversely of one of the
axles. Fig. 4 is a plan view of one of the
sleeves. Fig. 5 is an enlarged transverse sec-
40 tional view of one of the axles, illustrating
the construction of the locking device for re-
taining the stub-axle in the bearing-sleeve.
Fig. 6 is a detail perspective view of the key.
Fig. 7 is a detail view of the latch for hold-
45 ing the key in engagement with the stub-axle.
Fig. 8 is a detail view illustrating the ar-
rangement of the transverse angle-bar and
the metal strap for supporting the body of
the car.

Like numerals of reference designate corre- 50
sponding parts in all the figures of the draw-
ings.

1 designates a stub-axle having a wheel 2
suitably secured to its outer end, and the said
stub-axle is arranged within a bearing-sleeve 55
3, which is secured to the bottom of a car-
body 4 by the means hereinafter described.
The bearing-sleeve, which is closed at its inner
end, as clearly illustrated in Fig. 2 of the ac-
companying drawings, and which has its outer 60
end extending into a suitable recess 6 of the
hub of the wheel, is provided with lateral and
longitudinal extensions or plates 7 and 8,
formed integral with the bearing-sleeve and
located, respectively, at opposite sides of the 65
outer portion of the sleeve and at the inner
end thereof. The extensions or plates 7 and
8 are provided with openings 9 and 10, sur-
rounded by upwardly-projecting bosses or
lugs 11 and 12, arranged in corresponding re- 70
cesses 13 and 14 of the bottom of the car-body
and adapted to relieve the fastening devices
15 and 16 of strain and capable of holding the
bearing-sleeve against longitudinal or lateral
displacement. The fastening devices, which 75
preferably consist of bolts, extend through
perforations of the bottom of the car-body and
through the openings 9 and 10, and they have
countersunk heads and are provided with
nuts arranged in pairs, as clearly shown in 80
Figs. 2 and 3 of the drawings. The lower or
outer nut is adapted to form a jam-nut to pre-
vent the upper nut from unscrewing. Instead
of employing bolts, rivets or any other suit-
able fastening devices may be provided, and 85
the bearing-sleeve may be fastened to either
wooden or metallic car-bodies, and the num-
ber and arrangement of the plates or exten-
sions may be varied. Any thrust to which
the bearing-sleeve may be subjected will be 90
sustained by the upwardly-extending annular
bosses or lugs which project from the upper
faces of the plates or extensions, and such
thrust will not be received by the fastening
devices for securing the bearing-sleeve to the 95
car-body.

The stub-axle is provided at its inner end
with an annular groove 17, which is engaged

by a forked or bifurcated key 18, having a shank 19, which extends outward through a side opening 20 of the sleeve, which is also provided at its top with an opening 21 to permit the key to be arranged in the sleeve before the latter is secured to the car. The sleeve is slightly enlarged adjacent to the openings 20 and 21, and there is sufficient space to enable the engaging portion of the key 10 to be drawn backward clear of the stub-axle, as illustrated in dotted lines in Fig. 5 of the accompanying drawings. The bearing-sleeve is provided with a shoulder 22 to receive the upper side of the fork of the key, and 15 the shank of the latter is recessed at its outer end to provide a shoulder 23, which is engaged by a pivoted latch 24. The latch 24, which is pivoted to the outer face of one side of the bearing-sleeve by a rivet 25 or other suitable 20 fastening device, is provided with a suitable handle 25, and it has an eccentrically-pivoted head which when the handle is swung downward to a depending vertical position, as illustrated in Fig. 7 of the accompanying drawings, projects over the side opening 20 and is arranged to engage the shoulder 23 to prevent the key from being drawn outward. The outer end of the shank of the key is provided with a depending portion 27, which is adapted to be 25 readily grasped by the operator, and the latch may be readily swung around out of engagement with the shoulder of the shank. The latch will be maintained in engagement with the shank by gravity, and the fastening device 25 may be arranged to hold the latch tightly against the outer face of the sleeve to create sufficient friction to prevent the latch from accidentally turning when subjected to any jar or vibration incident to the passage 30 of the car over a piece of rough road-bed.

The bearing-sleeve is provided at its outer portion with a longitudinal enlargement 28, having a longitudinal oil-passage 29 and extending into a corresponding recess 30 of the 45 car-body to assist in supporting the sleeve. The longitudinal passage, which is arranged at an inclination, as clearly shown in Fig. 2, extends downward to the bore of the sleeve, which is provided with annular and longitudinal recesses 31 and 32. The enlargement is provided at the outer end of the passage 29 with a cover 33, located beyond the side of the car and arranged at a slight inclination. The cover is adapted to be swung upward to expose the outer end of the oil-passage, and it is capable of excluding foreign matter from the bearing. 50

The car-body is supported by an angle-iron brace 34 and a metal strap 35, extending across 60 the center of the bottom of the car and adapted to prevent the body of the car from being strained by the independently-mounted stub-axles. The metal strap or bar 35 has its end portions extended upward on the sides of the 65 car, as indicated in Fig. 8 of the accompany-

ing drawings, and its central horizontal portion is arranged contiguous to the angle-iron brace 34.

It will be seen that the stub-axles are exceedingly simple and inexpensive in construction, that they are self-oiling and adapted to be lubricated independently of one another, that they are readily attached to a car, and that the latter is securely braced and prevented from being strained or otherwise injured by the stub-axles. It will also be apparent that where the cars are constructed for wide-gage roads the expense will be greatly lessened by employing stub-axles, as the latter do not extend entirely across the 75 cars. It will also be apparent that the annular lugs or bosses, which are interlocked with the bottom of the car-body, hold the bearing-sleeves in alignment and relieve the fastening devices of strain. 80

The independent stub-axles are much cheaper than a single continuous axle, and it has been found by experience that when a single wheel or axle receives a severe strain or shock the damage, if any, is confined to 90 such wheel or axle and that with stub-axles there is less liability of breakage under such conditions than when the sleeves and axles are connected.

The stub-axles may be removed from their 95 bearings in event of breakage without unloading the car or taking the latter out of the train and without removing the bearing-sleeves from the car-body. The locking devices for retaining the said axles in the sleeves 100 are readily accessible and may be conveniently operated to release the stub-axles when desired.

What I claim is—

1. The combination with a car-body, of the 105 rigidly-mounted bearing-sleeves secured directly to the lower face of the bottom of the car-body at opposite sides thereof and provided with hollow lugs or bosses interlocked with the bottom of the car-body, fastening 110 devices passing through the lugs or bosses and supported by the same, and the independent stub-axles detachably secured within the bearing-sleeves, substantially as described. 115

2. The combination with a car-body, of rigidly-mounted bearing-sleeves secured directly to the lower face of the bottom of the car-body at opposite sides thereof and arranged independently of each other and spaced apart, 120 the independent stub-axles arranged within the bearing-sleeves, and the transverse brace extending across the bottom of the car-body and adapted to support the frame at the center between the ends of the sleeves, substantially as described. 125

3. The combination of a bearing-sleeve provided at one side with an opening, a stub-axle arranged in the bearing-sleeve, a key engaging the stub-axle and provided with a shank 130

extending through the opening of the sleeve and provided with a shoulder, and a pivoted latch mounted on the exterior of the bearing-sleeve and arranged to engage the shoulder

5 of the latch, substantially as described.

4. The combination of a car-body, the bearing-sleeve rigidly secured to the car-body at opposite sides thereof and mounted independently of each other and terminating short of

10 the center of the body and spaced apart, the independent stub-axles arranged within the bearing-sleeves, the angle-iron brace 34 ex-

tending across the body, and the metal strap arranged adjacent to the brace and extending across the body and embracing the sides 15 thereof, substantially as described.

In testimony that I claim the foregoing as my own I have hereto affixed my signature in the presence of two witnesses.

JAMES HENRY EGBERT.
